UNITED STATES PATENT OFFICE.

WILLIAM METCALF, OF LAKE, ILLINOIS.

CAR-COUPING.

SPECIFICATION forming part of Letters Patent No. 397,017, dated January 29, 1889.

Application filed May 25, 1888. Serial No. 275,087. (No model.)

To all whom it may concern:

Be it known that I, WILLIAM METCALF, a citizen of the United States, residing at the town of Lake, in the county of Cook and 5 State of Illinois, have invented a certain new and useful Improvement in Car-Couplers, which is fully set forth in the following specification, reference being had to the accompanying drawings, in which—

10 Figure 1 is a plan view of a construction embodying my invention; Fig. 2, a sectional view of the same, taken on the line 1 1 of Fig. 1; Fig. 3, a front elevation; Fig. 4, a view of the coupler detached, and Fig. 5 a side elevation showing a modification.

Like letters refer to like parts in all the figures of the drawings.

My invention relates to car-couplings, and more particularly that class known as "automatic" couplings.

My present invention is in the nature of an improvement upon that set forth in Letters Patent No. 365,270, granted to me June 21, 1887. In the construction shown in said Letters Patent no particular or special provision is made for the coupling of cars wherein the draw-bars to be coupled stand at different heights.

It is the object of my present invention to 30 remedy this defect; and to this end my invention consists in certain novel features which I will now proceed to describe, and will then particularly point out in the claims.

In the drawings, in which I have shown my 35 present invention practically carried out in one form, A represents the body of a railway-car, B the longitudinal sills thereof, and C the transverse sill at the end of the car.

D represents the draw-bar, which is mounted 40 between the sills B and supported in the usual manner. This draw-bar is free to move longitudinally to a limited extent, as is usual, and is provided at its rear end with the usual spring mechanism, E, to take up the tractiveal 45 strain and permit the draw-bar to act as a buffer.

The particular manner of mounting the draw-bar forms no part of my present invention, the construction shown being simply an 50 illustration of one manner in which it may be effected. The head D' of the draw-bar is of considerable vertical height and is provided

in its front face with a series of flaring mouths or jaws, d, arranged the one above the other. In the present instance I have shown three of 55 these mouths, although it is obvious that the number may be varied as desired. The head of the draw-bar is recessed, as shown at D², to receive the coupler F, and in the side walls of this recess there are formed lateral guiding-grooves d', extending rearward from each mouth d and serving to guide the link during the act of coupling. The coupler F is free to move vertically in the recess D² in the head of the draw-bar and is provided with an 60 enlarged head, F', which serves not only to limit the downward motion of the coupler, but also to cover and protect the recess in the draw-bar and prevent the entrance of dust, snow, or the like. The front edge of the 65 coupler is provided with a series of hooks, F², corresponding in number and location to the mouths d of the draw-bar. Each hook extends downward and rearward, its front surface, f, being curved or inclined, as shown, so 70 that when the coupler is in its lowest or normal position the said incline forms practically a continuation of the upper inclined wall of the corresponding mouth d of the draw-bar. 75

A recess, f', is formed in the coupler above and in the rear of the termination of each hook F², as clearly shown in the several figures of the drawings, said recess being of slightly larger dimensions than that portion 80 of the link which is intended to be received therein. Below the said hook and recess the body of the coupler is carried forward, as shown at f², thus forming an incline which is normally below the mouth of the draw-bar at 85 its forward end, the said incline extending from this point upward and rearward until it merges with the rear wall of the recess f'. The coupler is held normally in its lowest position either by gravity, as shown in Figs. 1 90 to 4, inclusive, by its own weight, or through the medium of a suitable spring. This latter construction is shown in Fig. 5 of the drawings, in which the coupler is provided with a downwardly-extending shank, G, threaded at 95 its lower end to receive a nut, g. A spring, G', coiled around said shank and bearing against the nut and the under side of the draw-bar, serves to draw the coupler down-

ward and hold it normally in its lowest position. Any suitable means may be employed to lift the coupler, either that shown in my former Letters Patent hereinbefore referred to or any other suitable construction for the purpose. This mechanism forms no part of my present invention, and I therefore have not shown the same.

H represents the coupling-link, which is preferably constructed as in my former Letters Patent hereinbefore referred to, although any suitable form of link may be employed.

The projecting lower end of the coupler F is provided with a transverse pin or key, f³, which, by striking against the under side of the draw-bar, serves to limit the upward motion of the coupler and prevent its being lifted too far.

20 The operation is as follows: When the coupler is in its normal position, as shown in full lines in Fig. 2 of the drawings, the hooks F² are opposite their corresponding mouths d. Since the draw-bars to be coupled may vary 25 in height, owing to the various causes which tend to produce this result, the coupling-link H will enter that one of the mouths d which is at the right height to receive the same. The flaring walls of the mouth guide the end 30 of the link into the lateral grooves d', and as the link enters the same it comes in contact with the inclined front surface, f, of that hook F² which is in line with the mouth which the link has entered. As the link 35 advances farther into the draw-bar, it will lift the coupler upward into the position shown in dotted lines. The link then passes to the rear of the hook F and enters the recess f'. As soon as this occurs, the coupler 40 descends to its original position. This latter action of the coupler will, as a rule, take place either through the action of gravity or through the force of the spring G', in case this latter be employed; but in order 45 to render this downward movement of the coupler positive I employ the incline f², against which the link strikes, and by bearing against the same as it moves rearward forces the coupler positively downward, while 50 at the same time the said incline serves to guide the link positively into the recess f'. The parts are then in the position shown in Fig. 2 of the drawings, with the link resting in the recess f' and in engagement with the hook F² of the coupler. In uncoupling it is 55 only necessary to raise the coupler F through the medium of the mechanism provided for that purpose until the link is clear of the hook, when the link may be readily withdrawn 60 to detach the car. When the spring G' is

employed, the nut g serves in an obvious manner to vary the pressure exerted by said spring and adjust it to the requirements of the case. It will thus be seen that I obtain an automatic coupling which is positive in its action, 65 and which may be employed to couple cars the draw-bars of which are not of the same height.

It is obvious that various modifications in the details of construction may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. In a car-coupling, the draw-bar provided with a vertical recess and having a vertical series of mouths communicating therewith, in combination with the coupler arranged in said recess and capable of direct vertical movement therein parallel to the face of the draw-bar, said coupler being provided with a series of downward and rearward extending hooks corresponding in number to the mouths and arranged at distances corresponding to the distances which separate the mouths, and with a corresponding series of downward and forward inclines to the rear of and below said hooks, the relative arrangement being such that in coupling the link first strikes the hook to raise the coupler and then the incline to depress the coupler, substantially as and for 95 the purposes specified.

2. In a car-coupling, the draw-bar provided with a vertical recess, a vertical series of mouths communicating therewith, and lateral guiding-grooves extending rearward from each mouth, in combination with the coupler arranged in said recess and capable of direct vertical movement therein parallel to the face of the draw-bar, the said coupler being provided with a series of downward and rearward extending hooks corresponding in number to the mouths and arranged at a distance apart equal to the distance separating said mouths, and with a corresponding series of downward and forward inclines to the rear of and below said hooks, the relative arrangement being such that in coupling the link first strikes the hook to raise the coupler and then the incline to depress the coupler, substantially as and for the purposes specified.

WILLIAM METCALF.
